UNITED STATES PATENT OFFICE

ARNOLD EDELSTEIN AND GEORG KIS, OF BUDAPEST, HUNGARY

HARNESS-CONTROLLING MECHANISM FOR LOOMS

Application filed September 7, 1927, Serial No. 217,912, and in Hungary September 7, 1926.

This invention relates to a harness controlling mechanism for looms and has for its object the provision of certain improvements in the mechanisms of this kind.

5 The present invention relates to dobbies or harness controlling devices of the type wherein catches are pivoted to curved parts mounted on a notched constantly-operating shaft and are controlled by pattern mechanism whereby selected catches can be moved into engagement with and thus locked to the notched shaft so that the corresponding curved parts are operated to actuate the corresponding harnesses.

10 According to the present invention cords for raising the harnesses are passed around the peripheries of intermittently rocking annular members. Further, according to the invention the notched shaft is oscillated about 20 its axis by means of an eccentric on a constantly-rotating shaft and the curved parts comprise rings or annular members connected by cords to the harnesses.

15 The invention is illustrated in the accompanying drawings, wherein:—

25 Figs. 1 and 2 illustrate, diagrammatically, a cross section of a mechanically operated harness controlling mechanism, with the harness in the lowered and raised position, respectively.

30 Fig. 3 is a sectional side elevation of the same mechanism.

Fig. 4 shows a modification in cross section.

35 Above the upper girder of the loom there is arranged in the longitudinal direction of the loom, that is, at right angles to the shafts of the harnesses, a shaft T Fig. 1 on which there is assembled a series of annular members or rings G, the number of which corresponds to the number of harnesses N to be lifted.

40 These rings and the shaft T form clutches, one part common to all, the shaft T being constantly rocked, and from time to time engagement takes place between it and the rings G, each of which is connected with its corresponding harness N. The shaft T has a rocking movement imparted thereto by means of an arm Y and an eccentric X keyed on a constantly rotating shaft. This is a uniform-

ly accelerated and retarded rocking movement, as it is derived from the eccentric X.

A groove M is machined longitudinally into the shaft T, and on each ring G is provided a pivotally mounted pawl K₁ adapted 55 to co-operate with the groove M. A spiral spring W normally tends to disengage the pawl K₁ from the groove M, that is, to move it to a greater distance from the rocking shaft T.

Opposite each of the pawls K₁ each ring G has pivoted thereto an arc-shaped arm C provided with a blade spring F. When the constantly rotating member H brings a lag R, 60 from which there projects a peg V, adjacent the arm C this peg presses the said arm towards shaft T so that the said arm C presses the pawl K₁ by means of the spring F and against the action of the spiral spring W 65 against shaft T. The pawl K₁ subsequently 70 engages with the groove M so that the ring G is locked to the shaft T.

75 By reason of the engagement between the rocking shaft T and the corresponding ring G the shaft T will move the ring G therewith. A cord Z fixed on the circumference of the ring G leads to harness N, so that as the ring G is rocked in a clockwise direction from the position shown in Fig. 1 to the position shown in Fig. 2, the harness is raised by 80 the cord Z from the position shown in dotted lines Fig. 2 to the position shown in full lines. A spring U serves to return the harness to its original position.

85 Before the shaft, during its return movement, reaches the end of this movement a projection J₁ on the ring G meets a fixed and accurately adjustable elastic stop J₂. The latter prevents the ring G from continuing to accompany the shaft T during the last 90 3 to 4 mms. of its travel. During this portion of the return movement the shaft moves alone. The spiral spring W is thus enabled to disengage the pawl K₁ from the groove M. A stop E arranged in front of arm C limits the rocking movement of arm C and indirectly also that of the pawl K₁.

95 Fig. 4 shows a modification, in which the springs W and F are unnecessary, by reason of the shape and position of the pawl K₂ and 100

arm C₂. J₃ denotes a modified form of stop.

It is to be understood that the invention may be modified in various ways without departing from the scope of the invention.

We claim:

- 5 1. A harness controlling mechanism of the type described, comprising a notched operating shaft, a plurality of annular members mounted on said shaft, pivoted pawls on said members adapted to engage in the notch of said operating shaft, and means connected to said members for operating the harnesses.
- 10 2. A harness controlling mechanism of the type described, comprising an operating shaft, an eccentric member for oscillating said shaft, a plurality of annular members loosely mounted on said shaft and operatively connected to the harnesses and means adapted to selectively engage said members and cause participation thereof in the movement of said shaft.
- 15 3. A harness controlling mechanism of the type described, comprising a constantly operating shaft, a plurality of annular members concentrically mounted on said shaft, a plurality of adjustable stops, projections on said annular members adapted to cooperate with said stops whereby the movement of said annular members may be arrested before the movement of said shaft, and means connected to the peripheries of said annular members for raising and lowering the harnesses.
